UNITED STATES PATENT OFFICE.

PARK E. WELTON, OF CUYAHOGA FALLS, OHIO, ASSIGNOR TO KATHARINE B. WELTON,
OF CUYAHOGA FALLS, OHIO.

FEED MECHANISM FOR MIXING-MILLS.

1,133,025.

Specification of Letters Patent. Patented Feb. 20, 1915.

Application filed November 4, 1914. Serial No. 570,283.

To all whom it may concern:

Be it known that I, PARK E. WELTON, a citizen of the United States, residing at Cuyahoga Falls, in the county of Summit and State of Ohio, have invented a certain new and useful Improvement in Feed Mechanism for Mixing-Mills, of which the following is a full, clear, and exact description:

When an endless feed apron is arranged to travel in contact with a part of the surface of one of the mixing rolls of a mixing mill for the purpose of repeatedly returning to the mixing rolls the material which passes between them, constantly varying practical conditions arise which have to be taken into account and provided for, if said feed apron is to remain unbroken and to perform, in a practical way, the functions for which it is provided; and this is especially true when the mixing mill is being used to mix compounds of raw rubber and other like; because the sticky rubber compound as it passes between the mixing rolls and tends to the action of the feed apron is particularly apt to collect in bunches of various sizes, disposed haphazard crosswise of the apron.

Since the feed apron is driven through its contact with a part of the periphery of a mixing roll, the apron must be kept fairly tight from side to side, and this, under the circumstances above mentioned, requires the use of tightening means, which are inherently and substantially incapable of being applied directly at the center. See also the opinion of the court of appeals to the effect that the pressure of a bunch of material is, to a certain extent, relieved by the tendency of the material, and of the other material of the mixing apparatus to draw it toward the center, and, in addition, the pressure of the material is relieved by the tendency of the material to move laterally, and the pressure of the material is relieved by the tendency of the material to move laterally.

The present invention is designed to automatically regulate the width of the apron surface, so that the latter will tend to move laterally in the same manner to prevent the material of the apron and to, in later respects, effectively do the work for which it is provided.

The invention consists in the construction

and combination of parts which are shown in the drawings, and hereinafter described and definitely pointed out in the detailed claims.

In the drawing, Figure 1 is a side elevation of the mechanism in which the present invention is embodied, and an end of the mixing mill is shown; Fig. 2 is a view assumed that the front frame, numbered 10, of the mixing mill has been removed. Fig. 3 is a plan view partly sectioned in the plane of line 3-3 on Fig. 1 of the mechanism embodying this invention. Fig. 4 is a longitudinal vertical section in the plane indicated by line 4-4 on Fig. 1. Fig. 5 is a horizontal sectional view in the plane indicated by line 5-5 on Fig. 1 of the mechanism carried by the rods 25. Fig. 6 is a vertical sectional view in the plane indicated by line 6-6 on Fig. 2; and Fig. 7 is a vertical sectional view in the plane indicated by line 7-7 on Fig. 2.

Referring to the parts by reference characters, 10 and 11 represent the mixing rolls of a mixing mill of ordinary construction adapted to be used for mixing rubber compounds. It will be understood, of course, that the mill will necessarily include means so far as the said rolls are turned in the direction indicated by the arrows from the representations of said rolls in Fig. 3. Hence the mixing rolls is a frame member 12, preferably in the form of a path which can be immovably upon the cross tie rod 13, or it may have any other suitable support.

An endless feed apron 20 embraces three horizontal rolls 16, 22 and 28. The rolls 16 and 22 are located in about the same horizontal plane below the mixing rolls. When the feeding mechanism is in use, the third roll 28 occupies a position above the center of the mixing roll 10 and slightly over and to the front side thereof. The apron 20, as through its contact with mixing roll 10, is caused to travel in the direction indicated by the adjacent arrow, *i.e.*, forward from roll 10 beneath the two mixing rolls 10 and 11, so as to be in a position to catch whatever material drops from between said rolls, then up in contact with about one-third of the surface of mixing roll 10, over roll 16 down under roll 22, and thence back to

up over roll 16. The roll 16 is rotatively mounted in brackets 14 located adjacent to opposite sides of the pan 12 near the rear end thereof, which brackets are preferably secured to two movable rods 47 to be presently described. The roll 22 is rotatively mounted in brackets 21. These are located near opposite sides of the front end of the pan, and loosely embrace the two rods 47 so as to be capable of sliding thereon. Each bracket is, however, under the influence of a spring 60 which embraces the associated rod 47,—said spring being compressed between said brackets and a collar 65 on said rod. The ends of the roll 28 are rather loosely mounted in bearing brackets 27, each of which is rigid with a cylinder 26.

Each cylinder is slidably mounted on a rod 25, whose lower end is rigidly fixed to 20 and is therefore, in effect, a part of a lever 23. The two levers 23 are independently pivoted on opposite sides of the pan,—or rather to bearing brackets 13^a rigidly secured to opposite sides of the pan. The two rods 25 extend upward from said levers, and at an angle toward the mixing roll 10, so that, when the device is in use, the upper ends of said rods will overhang the front part of the mixing roll 10.

30 A piston 29 is rigidly connected with each rod 25 within the associated cylinder. Each rod 25 has through it a duct 25^a, which, at its upper end, discharges into the cylinder 26 above the piston. At its lower end each 35 duct is connected with a supply pipe 45, from which compressed air or steam may be discharged into duct 25^a, and thence into the cylinder. The result will be to yieldingly move said cylinder up on its supporting rod 40 25 as far as is necessary to keep the adjacent part of the feed apron 30 tight.

The upward movement of each cylinder upon its supporting rod may be limited by its engagement with an adjustable nut 32 45 which may be screwed up and down upon the threaded end of the rod 25 by means of a hand wheel 32^a. The pull applied to the apron by the stated movements of the associated cylinders upward on the supporting 50 rod will draw the feed apron tightly against the mixing roll 10, and will cause the supporting levers 25—23 to swing on their pivots toward the mixing roll 10. Now, when the apparatus is in use, and 55 lumps of the mixture get between the apron and the mixing roll tending to tighten the apron near one or the other edge thereof, the corresponding cylinder 26 will yield downward, the corresponding lever 25—23 60 may swing slightly away from the mixing roll, and thereby this part of the belt will be so loosened to facilitate the passage of the lump without injury to the apron. The opposite edges of the apron, adjacent to the 65 mixing roll, will travel at different rates

when lumps of material are unequally distributed thereon, and between the apron and feed roll, and therefore the apron will tend to move laterally, if this tendency is not overcome. The mechanism contains several 70 features, each of which alone does much to prevent this lateral movement, and all co-operate to practically prevent any lateral movement of said apron. Perhaps the most important expedient for producing this result is the clamping of the apron from side to side between a roll 37, and the roll 22,—the latter being, as stated, under the influence of two springs 60 acting to yieldingly press it toward roll 37. When the moving 80 apron is so clamped between the two revolving rolls 37 and 22, all parts of the apron, as it passes between these rolls, will be compelled to move at the same rate. There will be a slight puckering of one side or of the 85 other side of the down running leg of the feed apron, between the rolls 28 and 37, but that is a matter of no importance. Said apron has preferably a rib 30^a along its under side adjacent to each edge, as shown 90 in Fig. 4. The parts of the apron rolls 16, 22 and 28, near their ends, beneath this rib are of reduced diameter (as at 28^b) to accommodate this rib. A little roller 45 carried by each cylinder 26 engages each ribbed 95 edge of the apron and holds it down behind the shoulder 28^c formed by reducing the diameter of roll 28.

In order to further insure that when an extra large lump of material passes between 100 the apron and mixing roll nothing will be broken, the endwise movable rods 47 are provided on opposite sides of the pan. Each is slidably mounted in bearing brackets 48 fixed to the pan; and brackets 14, in 105 which the rolls 16, 17 and 18 are mounted, are secured to these rods. When therefore there is an extra large lump of material between the apron and mixing roll, and thereby a severe strain on the apron, at one side 110 or the other this strain or pull will be transmitted through the apron to the roll 16, and thence to one or the other of said rods 47, which will thereby be pulled forward, in opposition to the spring 60 thereon, as before explained. Not only will this spring 115 resist this movement, and will return the rod to its normal position when the strain on the apron is relieved; but as the spring is additionally compressed it will push the 120 bearing brackets 21 forward and cause the roll 22 to clamp the apron between it and the roll 37 with greater pressure, and thereby to a greater degree oppose the tendency of the apron to move laterally. It is desirable, 125 however, that when one of the rods 47 is moved as stated the other shall move in like manner. Therefore at the rear end of the machine a rock shaft 70 is mounted in bearings fixed to the apron. Two arms 71 are 130

fixed to it, and are respectively located near the rear ends of the rods 47. Pins 47^a fixed to these rods go into slots 72 in the arms 71. This mechanism causes both rods 5 to move equally in the same direction.

In addition to the feed apron 30 there is an auxiliary feed apron 40 which runs over and embraces the two rolls 17 and 37 before referred to, and a third roll 18 adjacent to 10 roll 17 near the rear of the pan,—said rolls being placed so that the upper leg of the apron 40 will be held in contact with the lower leg of the apron 30, and will extend slightly beyond both ends. As shown, the 15 two rolls 17 and 18 are mounted in the same brackets 14 which support the roll 16; and roll 17 is located above roll 16 so that the apron 40 is held against that part of apron 30 which is passing up around roll 16. A 20 scraper 80 may be secured to the brackets 14 in front of roll 17, and extended over apron 30 between it and apron 40, so as to be able to scrape from this latter any material which might otherwise adhere thereto.

25 Sometimes some of the rubber may be carried up by the apron. Sometimes the powdered chemical which is being mixed with the rubber will be carried up by the apron over roll 28. In either event the material so carried over will go with the apron, or will fall by gravity into the projecting front end of the auxiliary apron. This material will then go along with apron 40,—and between it and the apron 30. It 30 will thereby be prevented from dropping off into the pan. The scraper 80 will insure that this compound shall again be carried around by apron 30 and up in contact with roll 10.

40 Two levers 33, are pivoted to opposite sides of the pan, at points which are approximately concentric with the roll 22, and they extend forward therefrom. The roll 37 extends between and is rotatably mounted 45 at its ends in these two levers 33. The front ends of these levers are connected respectively with the two cylinders 26 by means of the rods 34. In the construction shown, a box 43 is swiveled on a horizontal 50 axis to the front end of each lever 33. The lower end of each rod 34 passes through a box 43 and is held therein against endwise movement by two nuts 34^a. The upper end of each rod 34 passes through a box 35 55 which is swiveled on a horizontal axis to the associated cylinder,—and a nut 36 on said rod limits the downward movement of the latter in said box. These nuts may be so adjusted that they cause the auxiliary apron to be uniformly tightened from side to side when the main apron is held under proper tension against the mixing roll 10. Thereafter, under all of the conditions of use, that is to say, when either cylinder is 60 moving slightly up and down, or when the 65

supports 25 therefor are swinging on their pivot, or when the rods 47 are moving forward or backward, this auxiliary apron will be held tight enough for practical purposes. But the roll 37 will, under all conditions of 70 use, be in the required position to clamp feed apron 30 evenly from side to side between it and the roll 22.

In order to facilitate the removal of the mixed compound from the fed aprons, the 75 cylinders are allowed to slide down on the rods 25, which action will loosen both feed aprons. When the feed apron 30 is so loosened, certain flexible flanges 77 will sag into vertical or nearly vertical positions, 80 and any compound thereon will fall upon the apron. These flexible flanges 77 are, or may be secured to opposite sides of the pan, and extend inward over the sides of the apron, and normally rest at their inner edges 85 on said feed apron 30. They will catch any of the compound which falls from between the mixing rolls, and which otherwise might not land on the apron.

Having described my invention, I claim: 90

1. In combination with the mixing rolls of a mixing mill, of an endless feed apron, three rolls over which said apron runs,—two of said rolls being located in planes below the mixing rolls, two arms which are pivoted 95 at their lower ends and which, when in operative positions, extend therefrom upward adjacent to one of the mixing rolls, a member mounted on each of said arms and slidable up and down thereon, there being an inclosed 100 space between a part of each arm and said slidable member thereon, and means for delivering an elastic pressure fluid into said space,—the third apron roll being extended between and mounted in bearings carried by 105 the two slidable members.

2. In combination with the mixing rolls of a mixing mill, an endless feed apron therefor, three rolls over which said apron runs,—two of said rolls being located in 110 planes below the mixing rolls, two arms pivoted at their lower ends and extending upward alongside of one of the mixing rolls, each of said arms being provided with a piston, a cylinder slidably mounted upon 115 each piston and carrying bearings for the ends of the third apron roll, and means for delivering an elastic pressure fluid under pressure into each cylinder above the piston therein. 120

3. In combination with the mixing rolls of a mixing mill, an endless feed apron therefor, three rolls over which said apron runs,—two of said rolls being located in planes below the mixing rolls, two arms pivoted at 125 their lower ends and extending upward alongside of one of the mixing rolls, each of said arms being provided with a piston, a cylinder slidably mounted upon each piston and carrying bearings for the ends of the 130

third apron roll, each of said arms having a longitudinal duct which at its upper end communicates with the space within the cylinder and above the piston, and feed pipes 5 in communication with the lower ends of said ducts.

4. In combination with the mixing rolls of a mixing mill, an endless feed apron therefor, three rolls over which said apron runs,—
10 two of said rolls being located in planes below the mixing rolls,—two arms pivoted at their lower ends and extending upward adjacent to one of the mixing rolls, bearing brackets carried by said two arms,—the third

15 apron roll being extended between and mounted in said bearing brackets, an auxiliary endless apron, and rolls over which said apron runs, said rolls being so located that the upper leg of said supplemental

20 apron is held in contact with the lower face of the lower leg of the feed apron.

5. In combination with the mixing rolls of a mixing mill, an endless feed apron therefor, three rolls over which said apron runs,

25 two of said rolls being located in planes below the mixing rolls, two arms pivoted at their lower ends and extending upward alongside of one of the mixing rolls, bearing brackets carried by said two arms,—the

30 third apron roll being extended between and mounted in said bearing brackets, an auxiliary endless feed apron located below the feed apron first mentioned with its upper leg in contact with the lower leg of the first

35 mentioned apron, and extended at both ends beyond the lower leg of said first mentioned feed apron, and rolls over which said auxiliary apron runs.

6. In combination with the mixing rolls of a mixing mill, an endless feed apron therefor, three rolls over which said apron runs,

40 two of said rolls being located in planes below the mixing rolls, two arms pivoted at their lower ends and extending upward alongside of one of the mixing rolls, bearing brackets carried by said two arms,—the third apron roll being extended between and mounted in said bearing brackets, an auxiliary endless feed apron located below

45 the feed apron first mentioned with its upper leg in contact with the lower leg of the first mentioned apron and extended at both ends beyond the lower leg of said first mentioned feed apron, rolls over which said

50 auxiliary apron runs, and a scraper which extends over the upper leg of the auxiliary feed apron.

7. In combination with the mixing rolls of a mixing mill, an endless feed apron

60 therefor, three rolls over which said apron runs, one of said rolls when in working position being in a position which slightly overhangs one of the mixing rolls and the other two rolls being located in planes below the

65 mixing rolls, a pressure roll parallel with

and adjacent to one of the lower apron rolls, and relatively so located that the apron is clamped between said rolls.

8. In combination with the mixing rolls of a mixing mill, an endless feed apron therefor, three rolls over which said apron runs,—two of said rolls being located in planes below the mixing rolls, two arms pivoted to their lower ends and extending upward at an angle toward one of the mixing rolls, the third apron roll being mounted in the upper ends of said rods, and a roll mounted on an axis which is adjacent and parallel to one of the first two mentioned apron rolls, and means for relatively moving one of said two adjacent rolls toward the other to clamp said aprons from side to side between said rolls.

9. In combination with the mixing rolls of a mixing mill, an endless feed apron therefor, three rolls over which said apron runs, two of said rolls being located in planes below the mixing roll, two arms pivoted at their lower ends and extending upward alongside of one of the mixing rolls, bearing brackets carried by said two arms,—the third apron roll being extended between and mounted in said bearing brackets, two movable bearing brackets in which that one of the lower apron rolls is mounted which is nearest to the upper apron roll, a pressure roll parallel with and adjacent to the last mentioned lower apron roll, and springs acting on the bearing brackets of said apron roll to yieldingly move them toward said pressure roll to cause the apron to be clamped between the said two rolls.

10. In combination with the mixing rolls of a mixing mill, an endless feed apron therefor, three rolls over which said apron runs,—two of said rolls being located in planes below said mixing rolls, two arms pivoted at their lower ends and extending therefrom upward alongside of one of the mixing rolls, members slidably mounted upon said pivoted arms and carrying bearing brackets in which the third apron roll is mounted, means yieldingly impelling said slidable members to move up on said rods, an auxiliary apron, rolls over which said auxiliary apron runs, which rolls are so located that the upper leg of the auxiliary apron is held in contact with the lower face of the lower leg of the feed apron, two pivoted levers between which one of the rollers for the auxiliary apron extends, and in which it is mounted, and connections between said levers and the slidable members on the pivoted rods.

11. In combination with the mixing rolls of a mixing mill, an endless feed apron, three rolls over which said apron runs,—two of said rolls being located in planes below the mixing roll,—bearing brackets in which said lower rolls are mounted, end.

wise movable horizontal bars to which the bearing brackets of one roll are fixed, springs acting on said bars to yieldingly resist their movement in the apron loosening direction, two pivoted arms which extend from their pivotal support upward alongside of one of the mixing rolls, a member slidably mounted on each of said arms and carrying brackets in which the third roll is mounted, and means for yieldingly pressing said members upward on their supporting arms, and means compelling both bars to move simultaneously and equally in the same direction.

15 12. The combination with the mixing rolls of a mixing mill, an endless feed apron therefor, three rolls over which said apron runs, two of said rolls being located in planes below said mixing rolls, two arms pivoted at their lower ends and extending therefrom upward adjacent to one of the mixing rolls, members slidably mounted upon said pivoted arms and carrying bearings in which the third apron roll is mounted, means yieldingly impelling said slidable members to move upward on said rods, an auxiliary apron, rolls over which said auxiliary apron runs, which rolls are so located that the upper leg of the auxiliary apron is held in contact with the lower leg of the feed apron, two pivoted levers between which one of the rolls for the auxiliary apron extends and in which it is rotatably mounted, and connections between said levers and the slidable members on the pivoted rods.

13. In combination with the mixing rolls of a mixing mill, an endless feed apron therefor, three rolls over which said apron runs, two of said rolls being located in planes below the mixing roll, two arms pivoted at their lower ends and extending therefrom upward adjacent to one of the mixing rolls, members slidably mounted upon said pivoted arms carrying bearings in which the third apron roll is mounted, means yieldingly impelling said slidable members to move upward on said rods, slidable bearing brackets for that one of the two lower apron rolls which is nearest the upper apron roll, springs acting on said bearing brackets to move them in the belt tightening direction, an auxiliary apron, rolls over which said auxiliary apron runs, which rolls are so located that the upper leg of the auxiliary apron is held in contact with the lower leg of the feed apron, two pivoted levers in which one of the auxiliary apron rolls is rotatably mounted in such relation substantially as shown to the adjacent movable roll of the main feed apron that said apron may be clamped between said rolls, and connections between said levers and the slidable members on the pivoted rods.

14. In combination with the mixing rolls

of a mixing mill, an endless feed apron, three rolls over which said apron runs, two pivoted arms which extend from their pivotal support upward adjacent to one of the mixing rolls, a member slidably mounted on each of said arms and carrying bearings in which one of said three feed rolls is mounted, two horizontal endwise movable bars located below the mixing rolls, two bearing brackets respectively secured to said bars in which bearing brackets one of said three apron rolls is mounted, two brackets slidably in paths parallel with said bars, in which brackets the third apron roll is mounted, springs acting to move the last two mentioned bearing brackets in one direction and said two bars in the reverse direction.

15. In combination with the mixing rolls of a mixing mill, an endless feed apron, three rolls over which said apron runs, two pivoted arms which extend from their pivotal support upward adjacent to one of the mixing rolls, a member slidably mounted on each of said arms and carrying bearings in which one of said three feed rolls is mounted, two horizontal endwise movable bars located below the mixing rolls, two bearing brackets respectively secured to said bars in which bearing brackets one of said three apron rolls is mounted, two brackets slidably in paths parallel with said bars, in which brackets the third apron roll is mounted, springs acting to move the last two mentioned bearing brackets in one direction, and said two bars in the reverse direction, and means compelling both bars to move simultaneously and equally in the same direction.

16. In combination with the mixing rolls of a mixing mill, of an endless feed apron, three rolls over which said apron runs, two of said rolls being located in planes below the mixing rolls, two arms which are pivoted at their lower ends and which, when in operative positions, extend therefrom upward alongside of one of the mixing rolls, each of said arms having a piston fixed to it near its upper end, an extension member in the form of a cylinder which embraces said piston and is slidably mounted thereon, means for delivering an elastic pressure fluid into the space in said cylinder above said piston, the third apron roll being extended between and mounted in bearings carried by said two extension members, and means for limiting the upward movement of said extension members.

17. In combination with the mixing rolls of a mixing mill, an endless feed apron therefor, three rolls over which the feed apron runs, two of said rolls being located in planes below the mixing roll, two arms pivoted at their lower ends and extending therefrom upward alongside one of the mixing rolls, bearings carried by said two piv-

oted arms,—the third apron roll being extended between and mounted in said bearings, and flexible flanges which extend over the edges of the upper horizontal leg of the feed apron.

18. An attachment for mixing mills embodying a support adapted to be secured to a mill underneath the milling rolls thereof, an apron carried by said support, shelves above and extending over the side edges of the apron, and controlling means for the apron.

19. An attachment for mixing mills embodying a rigid frame adapted to be secured to a mill underneath the milling rolls thereof, an apron carried by said frame, shelves above and extending over the side edges of the apron, and controlling means for the apron.

20. The combination with the milling rolls of a mixing mill, of spaced rollers below said rolls, a roller above said spaced rollers mounted to slide toward and away from

said spaced rollers, an endless apron trained over said rollers, shelves above said spaced rollers extending over the side edges of said apron, and means for yieldably holding the slidably mounted roller at its upper limit of movement.

21. An attachment for mixing mills embodying a support adapted to be secured to a mill underneath the milling rolls thereof, spaced rollers carried by the support, a roller carried above and mounted to slide toward and away from the support, an apron trained over said rollers, shelves above and extending over the side edges of the apron, and means for yieldably holding the slidably mounted roller at its upper limit of movement.

In testimony whereof, I hereunto affix my signature in the presence of two witnesses.

PARK E. WELTON.
